DESIGN FOR A TAPESTRY COVERED PICTURE FRAME

Ida Jolles, New York, N. Y.

Application December 31, 1941, Serial No. 104,930

Term of patent 3½ years

To all whom it may concern:

Be it known that I, Ida Jolles, a citizen of no country, but have declared my intentions of becoming a citizen of the United States of America, residing in the city of New York, county of New York, and State of New York, have invented a new, original, and ornamental Design for a Tapestry Covered Picture Frame, of which the following is a specification, reference being had to the accompanying drawing, forming part thereof, wherein,

I claim:

The ornamental design for a tapestry covered picture frame, substantially as shown, and described.

IDA JOLLES.
